United States Patent Office

Des. 188,416
Patented July 19, 1960

188,416

AUTOMOBILE SEAT HEADREST

Karl Ramm, West St., Southington, Conn.

Filed May 19, 1959; Ser. No. 55,971

Term of patent 14 years

(Cl. D15—8)

The broken line disclosure of a chair back employed in Fig. 1 is shown for illustrative purposes only.

I claim:

The ornamental design for a headrest, substantially as shown and described.
